RETURNABLE BOX

Stephen A. Nagy, Detroit, Mich., assignor of one-half to V. R. Baur, Detroit, Mich.

Application November 2, 1935, Serial No. 47,916

10 Claims. (Cl. 217—5)

The invention relates to a returnable box for use in shipping heavy materials.

Shipping boxes suitable for the transportation of heavy materials, such as solder, lead, heavy 5 castings, etc., must, if they are to be sufficiently strong, be made of relatively heavy lumber and of sturdy construction, with the result that the cost of labor and material required for such boxes is considerable. It is the practice of shippers 10 of such materials to use boxes, all parts of which are secured together prior to shipment by means of nails or other permanent fastening means, with the result that opening of the box by the consignee of the goods renders it unfit for sub- 15 sequent use. Thus, a rather considerable expenditure for boxes is a total loss to the manufacturer, and consequently to the purchaser of the materials. Many attempts have been made to design a box of this character with a re- 20 movable top releasably held in place by means which can be disengaged without injuring the cover or remaining portions of the box, in order that the box may be returned and reused, but so far as applicant is aware no such structure has 25 been devised which is suitable for the shipment of heavy materials and which at the same time is sufficiently inexpensive or sufficiently easy to open and close to justify its use. It is the ob- 30 ject of the present invention to provide a re- 35 turnable box structure for shipping heavy ma- 40 terials in which is provided a removable lid adapted to be readily locked in position on the top of the box or released therefrom, and to pro- 45 vide such a structure which is relatively inex- 50 pensive to manufacture and which includes a lid locking means adapted to reinforce and strengthen the entire box structure so that it will with- 55 stand repeated use.

Another object of the invention is to provide 40 an improved mounting for an eye member for the reception of a crane hook to be used in lifting or handling the box when loaded.

Referring to the drawing, in which like numerals are applied to like parts in the several views: 45 Figure 1 is a perspective view of one form of the improved box structure.

Fig. 2 is a side view of the box shown in Figure 1 with a portion shown in vertical longitudinal section.

50 Figure 3 shows a modified form of the box.

Referring to Figures 1 and 2, there is provided a box having a pair of end walls 10 and 11, a pair of side walls 12 and 13, and a bottom wall 14. The end and side walls and bottom wall are 55 secured together in the position shown by any

suitable means such as nails or screws, not shown; and a pair of reinforcing straps 15 and 16 are wrapped around the side walls and bottom wall in the plane of the end members 10 and 11. These straps seat in suitable grooves in the side 5 walls and in the bottom wall, as shown at 17 in Fig. 2, and extend over the top of each end wall, as shown at 18 in Figure 2. The straps are nailed or otherwise secured in place around the box. A pair of reinforcing members 19 and 20 10 are secured in upright position to the opposite sides of end wall 10 and are secured in place by any suitable means such as nails or screws 21. It will be observed that these members 19 and 20 extend somewhat above the top edge of the 15 end wall 10 and the side walls 12 and 13 and that the side walls extend at their ends beyond the end walls 10 and 11 into overlapping relation with the reinforcing members 19 and 20. The bottom member 14 abuts at one end against 20 the reinforcing members 19 and 20 and extends at its sides outwardly beneath the side walls 12 and 13 and flush with their outer surfaces. The opposite end of the box from that shown in Figure 1 is similarly constructed, having upright 25 reinforcing members 22 and 23.

The box is provided with a lid 24 adapted to seat upon the top edges of the side and end walls in endwise abutment with the upper extensions on reinforcing members 19 and 20, 22 and 23, and 30 to extend substantially flush with the outer sides of side walls 12 and 13. The means for reinforcing the box and for releasably holding the lid in position thereon comprises four vertically extending bars 24, 25, 26 and 27 preferably made of 35 rolled steel. These bars are positioned in pairs at opposite sides of the box respectively, and are seated in vertical grooves in the side walls of the box and aligned grooves in the edge of the bottom wall, so that their outer surfaces lie substantially 40 flush with the outer surfaces of the side walls. They are fixedly secured to the side walls of the box by bolts 38 and to the edge of the bottom wall by screws 34. The side edges of lid member 24 are provided with similar aligned grooves 32 45 adapted to receive integral upward extensions of the reinforcing bars 24, 25, 26 and 27, respectively.

The upper ends of the reinforcing bars are provided with horizontally extending slots, as at 33 on reinforcing bar 24, adapted to receive the free 50 ends of a pair of locking members 34 and 35, which are pivotally secured to the lid of the box by means of bolts 36 and 37 respectively. The horizontal slots in the upward extensions of reinforcing rods 24, 25, 26 and 27 have their lower 55

edges substantially flush with the top surface of the lid, and the oppositely disposed reinforcing bar extensions are provided with oppositely directed slots such as 33, with the result that pivotal movement of the locking members 34 and 35 will swing their opposite ends respectively into said slots to lock the lid of the box against vertical movement with respect to the remainder thereof. The horizontal slots in the reinforcing bars are designed to have a fairly snug fit with the pivoted locking bars 34 and are so arranged that the locking bars are in tight contact with the top surface of the lid when they are in latched position. This supplies sufficient frictional engagement between the locking members and the lid to hold the members in locked position, but accidental displacement of the members may be further prevented by a pair of adjustable abutment devices 38 and 39 which are pivotally secured to the lid by bolts or screws and are adapted in the position shown to prevent accidental displacement of locking members 34 and 35. The abutment members 38 and 39 are so positioned with respect to members 34 and 35 that they may be struck by a hammer and wedged against the members to hold them in position.

In some instances it may be desirable to seal the lid in locked position on the box to prevent unauthorized opening thereof and the construction shown is readily adapted for the familiar wire type of seal. One possible mode of attaching such a seal is shown in the drawing, wherein an apertured block 40 is shown spot welded to one of the locking arms. The sealing wire is passed through a suitable aperture in the upper extension of the adjacent upright member 25 and through the aperture in block 40, and the wire ends are permanently secured together. The arrangement is such that the locking member 35 cannot be moved out of the slot in member 25 without breaking the wire.

It will be observed that by reason of the arrangement just described the vertical reinforcing bars 24, 25, 26 and 27 are fixedly secured to both the side walls and bottom member of the box, thus assisting in holding these members together and materially reinforcing the box structure in general. In addition, the arrangement transmits any pulling force on the reinforcing bars caused by a tendency of the lid to be removed not only to the side walls but also to the bottom of the box, thus materially increasing the strength of the parts. The box lid is held against movement laterally of the box by its edge abutment with the inner faces of the reinforcing bars, and is held against longitudinal movement with respect to the box not only by members 19, 26, 22 and 23, but also by the reinforcing bars 24, 25, 26 and 27 by reason of the recesses 32 which engage the latter bars. Likewise, it will be noted the positioning of the vertical bars in recesses in both the side walls and in the bottom member assist in preventing longitudinal movement of the bottom member with respect to the side walls, and the inner faces of the lower ends of reinforcing bars 24, 25, 26 and 27 assist in holding the bottom member against lateral movement with respect to the sides of the box. The result is a very sturdy construction adapted for repeated use but which is nevertheless quite simple and inexpensive to manufacture.

The top of the box is provided with a pair of transversely extending reinforcing and spacer members 45 and 46, nailed or otherwise secured 75 permanently to the lid of the box and having top

surfaces in a plane substantially parallel to the lid and spaced thereabove by an amount slightly greater than the distance the upper extensions of reinforcing bars 24, 25, 26 and 27 extend above the top surface of the lid. The function of these 5 spacer members 45 and 46 is to provide a surface upon which the box may rest or against which an adjacent box or wall may bear without contacting the ends of the reinforcing bars. This 10 protects the ends of the reinforcing bars and the pivoted latch members 34 and 35 from injury during handling of the box and simplifies handling and storage thereof. When it is desired to open the box the only instrument required is a hammer, two hammer blows being sufficient to 15 release abutment members 38 and 39 whereupon two additional blows on the adjacent edges of members 34 and 35, respectively, at one side of the box will release the lid. The box may be 20 closed by the same operation in reverse order.

As shown in Figures 1 and 2, there is provided an improved mounting for a pair of eye members 47 and 48, which may be engaged by a bar or a pair of crane hooks for lifting the box. When loaded these boxes may weigh 500 pounds 25 or more with the result that they are most conveniently handled by a crane. In such case, however, it is desirable to have a convenient and very sturdy connecting means for engaging the crane 30 hook. In the form shown, the eye members 47 and 48 comprise plate members having openings adjacent one end thereof and having their opposite ends secured in suitable recesses in the sides of the box, so that their outer surfaces are flush 35 with the outer surface of the side walls. The eye members are secured in position by screws 49 engaging with the side wall of the box, and by an elongated bolt or rod 50 which extends entirely through the box and passes through suitable openings in the ends of the respective eye 40 members 47 and 48. Internally of the box the bolt or rod 50 is positioned in direct abutment throughout its length with the inner surface of the end wall 10, as shown in Figure 2, with the result that the lifting force is applied not only 45 to the side walls but also directly to the end wall of the box structure. Suitable retaining means such as nuts are provided at the ends of the rod or bolt 50 to secure it in position.

In Figure 3 there is shown a modified form of 50 the box of simpler construction and particularly adapted for use with lighter materials or smaller sizes of boxes. The right hand end of this modified form, as viewed in the drawing, is constructed in the same manner as is the box shown 55 in Figures 1 and 2 and hence, need not be described, but the left hand end has been modified by eliminating the opposed reinforcing bars and cooperating pivoted latch member, and substituting therefor a pair of retaining and reinforcing bars 55 and 56 which are secured in abutment with the end wall 57 by means of bolts 58 and in abutment with the end edge of bottom wall 59 by means of screws 60. The upper ends of reinforcing bars 55 and 56 extend upwardly 60 beyond the top edge of the end wall 57 and thence are directed inwardly as at 61 and 62, respectively, into overlapping relation with respect to the adjacent ends of the lid 63. The top surface 65 of this end of the lid is recessed to receive the extension 61 and 62 so that the extensions will prevent lateral movement of the lid. It will be observed that in this form the lid retaining force is also transmitted not only to the end wall but 70 to the bottom wall of the box.

In assembling the lid on the type of box shown in Fig. 3, it is only necessary to insert one end thereof beneath the inward extensions 61 and 62 on reinforcing bars 55 and 56 respectively and then slide the opposite end of the box into end-wise abutting relation with the upward extensions of the reinforcing bars 64 and 65 until the lid rests upon the top edges of the side and end walls. In this position, the vertical reinforcing bar 66 will be positioned within the groove 67 in the lid, as described with respect to the modifications shown in Figures 1 and 2. It is only necessary, then, to drive the pivoted latching member into interlocking engagement with the slots in the upward extension of the vertical reinforcing bars to complete the lidding operation.

It will be observed that there has been provided a removable lid for a heavy shipping box wherein the lid securing mechanism not only reinforces the entire box but transmits the lid securing forces to the side and bottom members thereof. Accordingly, the box is very rugged and will withstand repeated shipments and at the same time is simple, inexpensive to manufacture and very easily lidded and opened.

What is claimed is:

1. A returnable box for shipping heavy materials including a pair of side walls, a pair of end walls and a bottom wall secured together, said end walls having portions extending above the top edges of the sides of the box, a reinforcing bar at each side of the box fixedly secured to the adjacent side edge of the bottom wall and to the side wall of the box, said bars having integral, horizontally slotted, vertical extensions above the top edges of the side walls, a removable lid adapted to rest upon the top of the box between the bar extensions and in abutment with said portions of the end walls, and a locking bar permanently secured to said lid for movement in a plane parallel thereto and having end portions adapted respectively to have an interlocking engagement with said bar extensions at said slots to lock the lid on the box.

2. A returnable box for shipping heavy materials including a pair of side walls, a pair of end walls and a bottom wall secured together, said end walls having portions extending above the top edges of the sides of the box, a reinforcing bar at each side of the box fixedly secured to the adjacent side edge of the bottom wall and to the side wall of the box, said bars having integral, horizontally slotted, vertical extensions above the top edges of the side walls, a removable lid adapted to rest upon the top of the box between the bar extensions and in abutment with said portions of the end walls, a locking bar permanently secured to said lid for movement in a plane parallel thereto and having end portions adapted respectively to have an interlocking engagement with said bar extensions at said slots to lock the lid on the box, and reinforcing means secured to said lid at spaced points thereon and having upper surfaces located in a plane substantially parallel to the lid and spaced above the top surface thereof by an amount not less than the height of said bar extensions above said lid surface.

3. A returnable box for shipping heavy materials including a pair of side walls, a pair of end walls, and a bottom member secured together, each of said side walls being provided with a groove in its outer surface, a reinforcing bar seated in each of said grooves, means fixedly securing the bars to the respective side walls, each

of said bars having an integral, horizontally slotted, vertical extension above the top edge of the adjacent side wall, a removable box lid adapted to seat on the top of the box between said bar extensions and having grooves therein for the reception of said bar extensions, and locking means permanently secured to the lid and adapted to releasably engage said slots to hold the lid in position on the box.

4. A returnable box for shipping heavy materials including a pair of side walls, a pair of end walls and a bottom wall secured together, each of said side walls being provided with a groove extending entirely across its outer surface, said bottom member being provided with grooves in its outer edges aligned with said side wall grooves respectively, a reinforcing bar seated in each of said first named grooves and extending into the aligned grooves in said bottom member, means fixedly securing the bars to the said side walls and bottom member, each of said bars having an integral, horizontally slotted vertical extension above the top edge of the adjacent side walls, a removable box lid adapted to seat on the top of said box between said bar extensions and having grooves therein for the reception of said bar extensions, and locking means permanently secured to the lid and adapted to releasably engage said slots to hold the lid in position on the box.

5. A returnable box for shipping heavy materials comprising, a pair of side walls, a pair of end walls, and a bottom member connected together, means associated with one end wall defining a horizontally extending inwardly opening slot for the reception of one end of a box lid, the other end wall having a portion extending vertically above the top edges of said side walls, a pair of members secured respectively at opposite sides of the box and having extensions above the top edges of the side walls, a box lid adapted to rest on said side walls between said extensions with one end positioned within said slot and the other in abutment with said portion of said other end wall, and means permanently connected to the lid for releasably engaging said last named extensions for holding the lid against vertical movement with respect to said box.

6. A returnable box for shipping heavy materials comprising, a pair of side walls, a pair of end walls, and a bottom wall connected together, a member secured to the outer surface of one of said end walls and having an extension directed upwardly and then inwardly from the top edge of said end wall, the other end wall having a portion extending vertically above the top edges of said side walls, a pair of reinforcing bars at opposite sides of the box respectively secured to the side edges of the bottom member and to the side wall, said bars having integral, horizontally slotted vertical extensions above the top edges of the side walls, a box lid adapted to rest on said walls between said bar extensions with one end positioned beneath the horizontal extension on said member and the other end in abutment with said portion of said other end wall, and a locking bar permanently secured to said lid for movement in a plane parallel thereto and having end portions adapted respectively to have interlocking engagement with said bar extensions at said slots to lock the lid on the box.

7. A returnable shipping box including a pair of side walls, a pair of end walls, and a bottom wall secured together, means on said end walls extending above the top edges of the side walls,

- a bar at each side of the box fixedly secured to the respective side walls and having integral extensions above the top edges of the side walls, a removable lid adapted to rest upon the top of the 5 box between the bar extensions and with its ends in abutment with said means on the end walls, a locking means permanently secured to said lid for movement in a plane parallel thereto into interlocking engagement with said bar extensions 10 to lock the lid on the box, and reinforcing means secured to said lid at spaced points thereon and extending above the lid by an amount not less than the height of said bar extensions above said lid.
- 15 8. A returnable box construction comprising, a pair of side walls, a pair of end walls, and a bottom wall connected together, a member secured to the outer surface of one of said end walls and having an extension directed upwardly and then 20 inwardly from the top edge of said wall, the other end wall having means extending vertically above the top edges of said side walls, a pair of locking elements at opposite sides of the box respectively secured to the side walls, said elements having 25 integral horizontally slotted vertical extensions above the top edges of the side walls, a box lid adapted to rest on said walls between the extensions of said elements with one end positioned beneath the horizontal extension on said member 30 and the other end in abutment with said means on the other end wall, a locking bar permanently secured to said lid for movement in a plane parallel thereto and having end portions adapted respectively to have interlocking engagement with 35 the extensions of said elements at said slots to lock the lid on the box.
9. A returnable shipping box including a pair of side walls, a pair of end walls, and a bottom wall secured together, means on said end walls

extending above the top edges of the side walls, a bar at each side of the box fixedly secured to the respective side walls and having integral extensions above the top edges of the side walls, a removable lid adapted to rest upon the top of the 5 box between the bar extensions and with its ends in abutment with said means on the end walls, a locking means permanently secured to said lid for movement in a plane parallel thereto into interlocking engagement with said bar extensions 10 to lock the lid on the box, and means secured to said lid at spaced points thereon and extending above the lid by an amount not less than the height of said bar extensions above said lid.

10. A returnable shipping box including a pair of side walls, a pair of end walls, and a bottom wall secured together, a member fastened at each side of the box fixedly secured to the respective side walls, said member having horizontally slotted extensions above the top edges of the side walls, a removable lid adapted to rest upon the top of the box between the extensions of said members, and a locking bar pivoted intermediate its ends on said lid and adapted upon 25 rotation to engage in said slots respectively for locking said lid in position, said bar having an integral upstanding projection adjacent that portion of one end of the bar which engages in one of said slots and in such position on that bar 30 that the projection will lie along side of the upstanding slotted member when the bar is engaged in said slots, and said upstanding projection and the upper extension of the adjacent of said slotted members being provided with apertures adapted 35 to receive the flexible wire of a wire sealing device for sealing the box against unauthorized opening.

STEPHEN A. NAGY.
